UNITED STATES PATENT OFFICE.

JAMES F. LEEPER, OF LEWISTOWN, PENNSYLVANIA.

GAS APPARATUS.

1,160,915.

Specification of Letters Patent. Patented Nov. 16, 1915.

Application filed July 17, 1915. Serial No. 40,486.

To all whom it may concern:

Be it known that I, JAMES F. LEEPER, a citizen of the United States, residing at Lewistown, in the county of Mifflin and

5 State of Pennsylvania, have invented a new and useful Gas Apparatus, of which the following is a specification.

This invention relates to gas supplying apparatus especially designed for use in connection with cook stoves.

In some localities, particularly in rural districts, it is necessary to use coal, wood, or oil as a fuel for cooking purposes, for the reason that gas is not available.

15 One of the objects of the present invention is to provide means whereby ordinary gas such as used for heating purposes can be supplied to persons to whom piped gas is not available, it being possible to ship 20 the gas to the consumer who is provided with a storage tank having means of novel form whereby the pressure of the gas within the tank is maintained constant so that the gas supplied to the burners of the stove 25 from the tank will issue therefrom at the pressure desired and irrespective of the quantity of gas contained within the storage tank.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed, can be made within the scope of what is claimed, without departing from the spirit of the invention.

40 In the accompanying drawing, which is a view showing diagrammatically the complete apparatus, the preferred form of the invention has been shown, certain of the parts being illustrated in section.

45 Referring to the drawing by characters of reference 1 designates a storage tank such, for example, as can be readily set up in a kitchen where it will have the appearance of an ordinary domestic boiler. This storage 50 tank has an outlet pipe 2 in the top thereof with which communicates a pressure in-

icator 3, said outlet pipe being provided with a valve 4 and being connected by a pipe 5 to a burner or burners 6 of a cook stove or the like.

55

An inlet pipe 7 opens into the tank 1 and is provided with a check valve 8 whereby the escape of gas from the tank through said pipe 7 is prevented. This pipe 7 is adapted to be connected, as by means of a coupling 9, to the valved outlet pipe 10 at one end of a supply tank 11.

Opening into the bottom portion of the storage tank is a water inlet pipe 12 having a valve casing 13 in which is provided a 65 valve 14 provided at the lower end of a rod 15. This rod may be guided in a bracket 16 outstanding from the tank 1 and located above the rod is a casing 17 having a diaphragm 18 which forms the bottom of a 70 pressure chamber 19 within the casing. This diaphragm constantly engages the upper end of the rod 15 and the pressure chamber 19 is constantly in communication with the interior of the upper portion of the tank 1 75 through a pipe 20. A spring 21 may be mounted on the rod 15 so as to bear downwardly on bracket 16 and upwardly against a collar 22 on the rod 15. This spring serves to hold the rod 15 normally elevated and 80 the valve 14 open, the diaphragm 18 at this time being buckled upwardly into the casing 17. Thus water is free to enter the tank 1 from the pipe 12. When, however, pressure in the casing 17 reaches a predetermined degree, the diaphragm 18 will be moved downwardly against the action of spring 21, thus 85 to close valve 14 and cut off the supply of water to the tank 1.

As before pointed out, it is designed to 90 have a storage tank 1 together with the regulating means, set up for each consumer and it is the intention to supply the various consumers with tanks 11 charged with gas under pressure. These tanks 11 properly 95 charged can be delivered when requested and, upon delivery, can be coupled up to the storage tanks by the consumers.

It is designed to have all of the tanks 11 charged with gas under equal pressure and 100 the tanks 1 and 11 are so proportioned that when a tank 11 is coupled to the pipe 7 of a

storage tank 1 and the valve 10 is opened, the gas contained in the supply tank 11 will expand into the storage tank 1 where it will be held under working pressure or, in other words, under the proper pressure at which it should issue at the burner 6. It has been found in practice that when gas is thus admitted to a storage tank 1, any air contained in the storage tank will first pass out of said tank through the burner 6, the valve of which is first opened. As soon as all of the air has issued from the burner 6 and the combustible gas begins to leave the burner, which fact can be readily determined by means of a flame, the valve to the burner can be closed and, if desired, the tank 11 can be removed and returned to the central station where it may be recharged. Check valve 8 will of course prevent the escape of the gas contained under pressure in the storage tank 1. After the gas has been placed in the storage tank in the manner set forth, a valve 23 provided in the water supply tank 12 is opened but as the pressure of the gas in tank 1 and downwardly on the diaphragm 18 is sufficient to overcome spring 21 and to hold valve 14 to its seat, this opening of valve 23 will not result in the flow of water through pipe 12 into tank 1. By opening the valve to one of the burners 6 of the stove connected to tank 1, gas will be discharged through the burner under the working pressure and can be ignited as ordinarily. As the pressure in the tank is lowered, the resistance offered to the lifting action of spring 21 will diminish and said spring will thus operate to lift the valve 14 from its seat and admit an amount of water through pipe 12 into the bottom portion of tank 1. This water will serve to hold the gas in said tank 1 under pressure so that the desired pressure in the tank and at the burner will be maintained. This water will continue to enter the tank as fast as the gas is removed therefrom, so that practically all of the gas contained in the tank can be used and the pressure will always be maintained the same. After the gas has been consumed, a drain cock 24 can be opened so as to draw off the water, valve 23 being first closed. A new supply tank can then be coupled to the storage tank and its contents directed thereto, as before described.

Although water is preferably used as a means for placing the gas under pressure, it is to be understood that if desired air under pressure can be used in lieu thereof under certain conditions and by the term "water" as used in the claims, it is intended to cover any form of fluid by which the desired results may be secured.

What is claimed is:

1. Apparatus of the class described including a storage tank having a valved gas

inlet and a valved outlet, a water inlet pipe 65 opening into said tank, and means operated by the pressure of gas within the tank for controlling the supply of water through the pipe and into the tank.

2. Apparatus of the class described including a storage tank having a valved gas inlet, a water inlet, a valved outlet, a pressure indicator, and means operated by gas within the tank when reaching a predetermined pressure, for closing communication 75 between the water supply pipe and the tank.

3. Apparatus of the class described including a gas storage tank having an inlet pipe, a check valve for preventing the escape of gas therethrough, a water pipe 80 opening into the tank, a valve for preventing the passage of water through the pipe, a second valve in said pipe, and means operated by pressure of gas in the tank for closing the last named valve, and means for 85 automatically opening said valve when the pressure is reduced.

4. Apparatus of the class described including a storage tank having a valved gas inlet, a gas outlet, and a water inlet, a pressure chamber, a diaphragm carried thereby, a valve in the water inlet, said valve being normally open, the diaphragm constituting means for closing the valves when subjected to a predetermined pressure of gas in the 95 tank.

5. Apparatus of the class described including a storage tank having a valved gas inlet, means for coupling a supply tank to said inlet, a water inlet pipe opening into 100 the storage tank, an outlet pipe extending from the top portion of the tank, an expandable pressure chamber in communication with the upper portion of the tank, means operated by the expansion of said chamber 105 for closing communication between the water pipe and the tank.

6. Apparatus of the class described including a storage tank having a valved gas inlet, means for coupling a supply tank to 110 said inlet, a water inlet pipe opening into the storage tank, an outlet pipe extending from the top portion of the tank, an expandable pressure chamber in communication with the upper portion of the tank, means 115 operated by the expansion of said chamber for closing communication between the water pipe and the tank, and means for automatically opening communication between the water pipe and the tank when pressure 120 within the tank is reduced to a predetermined degree.

7. The combination with a storage tank having an inlet pipe and a check valve within said pipe, of a supply tank coupled to 125 said pipe and adapted to supply gas under pressure to the storage tank, a valved gas outlet, a water inlet pipe opening into the

storage tank, a valve therein, an expansible compression chamber in constant communication with the upper portion of the storage tank, means operated by the expansion of said chamber for closing the valve, and means for automatically opening the valve during the contraction of said chamber.

In testimony that I claim the foregoing as my own, I have hereto affixed my signature in the presence of two witnesses.

JAMES F. LEEPER.
